UNITED STATES PATENT OFFICE.

EDWARD C. BARTLETT, OF MIDDLETON, CONNECTICUT, ASSIGNOR TO DAVID GRANT,
OF MIDDLEFIELD, CONNECTICUT.

VISE.

1,206,399.

Specification of Letters Patent. Patented Nov. 28, 1916.

Application filed October 28, 1914. Serial No. 369,027.

To all whom it may concern:

Be it known that I, EDWARD C. BARTLETT, a citizen of the United States, residing at Middletown, in the county of Middlesex, in the State of Connecticut, have invented certain new and useful Improvements in Vises, of which the following is a specification.

My invention relates to an improvement in vises or chucks and analogous tools which comprise the coöperation of a pair of clamping jaws movable relative to each other by means of actuating mechanism, such as a screw. It is a common fault with this class of instrumentalities that the movable jaw develops a tendency to lift the work with reference to the fixed jaw when the holding pressure is applied to the work or object clamped between them. For instance, in the case of a chuck employed for holding work which is being finished in a shaper or planer, it is only with the greatest care and difficulty that the work can be kept accurately seated between the jaws after the pressure is applied to it, as the tendency of such pressure is to lift the work and the movable jaw up from the plane of the fixed jaw, that is, the work tends to spring out from between the chuck jaws, instead of bedding itself in its seat, which interferes materially with the production of exact or accurate surfacing of the work. My improvement contemplates a construction which shall insure the positive bedding of the work in its seat, and obviate all tendency of the movable jaw to lift it therefrom.

In the accompanying drawings forming a part of this specification, Figure 1 is a side elevation of my improved vise, and Fig. 2 is a plan view of the same, viewed from above. Fig. 3 is a central longitudinal section through Fig. 2. Fig. 4 is a transverse section through Figs. 3 and 4 on the line 4, 4, thereof. Fig. 5 is an end elevation. Fig. 6 shows a modification of the jaw camming device.

Referring to the drawings, my improved vise is shown to embody the usual base plate 10, adapted when used as planer chuck to be bolted to the planer bed through the slotted flanges 11 at its ends, and provided with the vertical jaw 9 projecting upwardly above the plane upper surface 12 of the base at the rear end thereof. Said base, in the usual form, or as here shown, has a recess

13 on its lower side with vertical walls 14 and 15 respectively at its front and rear ends, and these walls form the bearings or abutments for supporting the operating screw 16 by which the movable jaw of the vise is actuated. In the present instance, a cap bearing 17 is let into the upper surface of the base at the front wall 14 and the base and cap each respectively form a half box for the journal 18 of the screw, which is necessarily placed between thrust collars 19 and 20, which are adapted to bear against the wall and the cap, and receive the end thrust of the screw. The provision of the half box 17 enables the screw to be placed in position from the front end of the base, after which the box may be secured by the screws 21. The base is formed with a central longitudinal slot 22 extending for such portion of its length as may be necessary for the range of the movable jaw, and in this slot is fitted a sliding block or nut 23, projecting above the surface 12, and screw threaded to receive the screw 16, upon which it is adapted to travel by the normal rotation thereof. Said block is provided with lateral flanges 24 which bear upon the lower side of the top of the base at each side of the slot 22. On the upper side of this top or surface 12, the movable jaw 25 is adapted to travel, and it is provided with longitudinal ribs 26 which fit corresponding longitudinal grooves 27 in the base for holding it in place, and confining its movement to the line of the grooves. The movable jaw is formed with a recess 28 on its lower side which receives the nut block 23, loosely fitted therein, that is, having ample clearance space around the block to permit motion of the jaw relative to the block in any direction. The nut block is formed with a transverse slot 29 extending through it, and having a plane of inclination from the horizontal or plane of the screw, converging toward the screw at the front end thereof, that is, the inclination of the slot is upward or away from the base in the direction of the fixed jaw, as shown in Fig. 3. Through this slot is passed a pin 30, or engaging element having its ends rigidly secured in the movable jaw, whereby pressure applied to the pin by the contact of the sides of the slot of the nut block therewith will operate to slide the movable block upon its guide ways on the base.

In operation, pressure applied upon the

pin 30, by means of the screw 16 in the direction of the fixed jaw to slide the movable jaw in that direction, will also draw downwardly on the movable jaw owing to the inclination of the engaging surface of the nut block therewith from the plane of the screw, as the nut block is held from lifting from the base, by means of the lateral flanges 24 in engagement with the lower side of the base. Said downward thrust upon the movable jaw holds it firmly to its seat in counteraction of any lifting tendency which may be imposed upon it by the work when it is clamped between the jaws, as is invariably the case in any construction of the kind where the movable jaw is directly engaged by the screw, as hitherto employed. With the improved construction the movable jaw is always kept firmly seated upon the base, with its working surface held squarely therewith and parallel with the fixed jaw, insuring accurate placing of the work and reliability of action under all conditions. It will be obvious that a converse arrangement of the engaging pin and slot of the movable jaw and nut block would be perfectly feasible and equally as well adapted to insure the result contemplated, that is, having the pin 31 fixed in the nut block and engaging inclined slots 32 in the jaw, as shown in the modification in Fig. 6. The operating screw in the present instance, as is usual with planer chucks or vises, is provided with an angular head 33 adapted for the reception of a wrench for turning the screw.

I claim as my invention and desire to secure by Letters Patent—

1. In vise mechanism the combination of a frame, a screw journaled in the frame, a movable jaw slidable in the direction of the axis of the screw, a nut carried upon the screw, and engaging means for connecting the nut with the movable jaw having the force transmitting abutment oblique to the line of the screw thrust in the direction to force the jaw to its seat by the act of forcing it against the work.

2. In vise mechanism the combination of a frame, carrying a fixed clamping jaw, a power screw journaled in the frame, a movable jaw slidably seated and guided upon

the frame, in clamping relation to the fixed jaw, a nut carried upon the screw in engagement with the movable jaw, the jaw and nut being provided with coacting engaging camming surfaces for such engagement adapted to transmit the force of the screw to the movable jaw diagonally to the plane of its movement, and in the direction to force the jaw upon its seat by the action of clamping the work between the fixed and movable jaws.

3. In vise mechanism the combination of a frame, a fixed clamping jaw carried upon the frame, a screw journaled in the frame and adapted to thrust upon the fixed jaw, a movable nut block carried upon the screw, a movable clamping jaw guided upon the frame and slidably mounted with relation to the fixed jaw, and engaging means between the movable jaw and nut block comprising diagonal camming surfaces by which the pressure of the actuating screw upon the block is transmitted to the clamping jaw in a line diagonal to the movement of the jaw to actuate the movable jaw at right angles to the axis of the screw, and upon its seat in the act of clamping the work, substantially as and for the purpose specified.

4. In vise mechanism the combination of a frame having a fixed clamping jaw mounted thereon, a power screw journaled in the frame and adapted to thrust upon the fixed jaw, a nut block carried upon the screw, a movable clamping jaw guided upon the frame slidable in relation to the fixed jaw, and engaging means between the movable jaw and nut block comprising coacting surfaces oblique to the axial line of the screw in the direction to transmit the screw pressure on the movable jaw in part to force the jaw against its bearing on the frame and seat it thereon in the act of clamping the work, substantially as and for the purpose specified.

Signed at Middlefield, Connecticut, this sixteenth day of October, 1914.

EDWARD C. BARTLETT.
